MULTIPLE JET CARBURETOR

Charles H. Burson, Seattle, Wash.

Application October 14, 1946, Serial No. 703,167

10 Claims. (Cl. 261—41)

1

This invention relates to improvements in carburetors for internal combustion engines and the like, having particular reference to the control of the mixture under conditions of varying speed and load.

It is generally recognized that a carburetor having a single fuel jet will not properly satisfy the varying demands of an internal combustion engine working in a wide range of speeds and power outputs. A jet designed to give a proper air-fuel ratio at low speeds produces too rich a mixture at higher speeds, and a jet suitable for high speed operation starves the engine at low speeds. In general it may be said that a single jet carburetor will give the proper mixture at only one speed, the mixture being too rich at higher speeds and too lean at lower speeds. This limitation results from an inherent jet characteristic whereby the fuel discharge is increased and decreased disproportionately to variations in the velocity of air flow past the jet in the carburetor venturi.

It has, therefore, become common practice to provide the carburetors of internal combustion engines with at least two jets in which one jet serves for idling and only very low speeds, and the other jet functions exclusively in the normal operating range of the engine. The use of two jets may provide a correct mixture for idling and a correct mixture for some particular speed and load condition in the operating range, but under all other conditions the engine demands are not properly and efficiently satisfied. Carburetors have also previously been made with more than two jets in an attempt to overcome or compensate for the inherent limitations mentioned above, but such carburetors have, for the most part, been complicated and difficult to adjust and maintain in proper adjustment, and usually have not operated in practice to maintain an optimum air-fuel ratio or to control the fuel delivery in close conformity with the engine demands over a wide range of variation in speed and horsepower output. Complicated and intricate carburetor mechanisms are objectionable because of the tendency of moving parts to either wear or stick fast where they cannot be kept lubricated, and because of the tendency of fine passages and jets to become clogged.

It is, therefore, a general object of the present invention to provide an improved carburetor which will closely control the air to fuel ratio in accordance with engine demands under variable operating conditions.

Another object is to provide a carburetor which

2

will automatically obtain maximum economy from an engine in one operating range and maximum power in another operating range without any change of adjustment.

5 Another object is to provide an improved carburetor construction which is particularly adapted to internal combustion engines such as automotive engines having extreme ranges of speed and power requirements.

10 Another object is to provide an improved carburetor of the type described which is of relatively simple and inexpensive construction, which is rugged and reliable in operation and which may be made entirely automatic in its mixture control so as to require no unusual adjustments in use.

In accomplishing the general objects hereinabove stated it is a particular object of the present invention to provide an improved carburetor construction utilizing multiple fuel jets for introducing gasoline into the moving air stream under the control of automatic means to vary the number of active jets in accordance with engine demands under different operating conditions to maintain optimum predetermined air to fuel ratios under all different combinations of speed and load which may be encountered in the use of the engine.

15 Another object is to provide a variable venturi to include more or fewer active jets in the Venturi opening in accordance with the volume of air drawn in by engine suction.

20 With these and other objects in view the invention resides in the arrangement of parts and details of construction shown by way of illustration in certain preferred embodiments on the accompanying drawings and described in the following specification.

Figure 13 is a fragmentary sectional view taken as Figure 3 showing a modified construction having a non-adjustable fuel allocator;

Figure 14 is a view similar to Figures 3 and 13 showing a further modification having only three 20 jets;

Figure 15 is a sectional view showing a further modification having inverted reeds; and

Figure 16 is a view taken as Figure 1, of a 25 modification especially adapted to utilize the central ports in the fuel allocator as idling ports, to make the use of a throttle edge idling port unnecessary.

In the embodiment shown in Figures 1, 2 and 3, the numeral 10 designates a vertical carburetor barrel forming an induction passage to the intake manifold of an internal combustion engine. The barrel 10 has a circular upper end 11 to communicate with an air filter or other source of air supply for the engine and a lower end having a flange 12 of standard construction for connection with the intake manifold of the engine. The numeral 13 designates a conventional float bowl mounted on or forming a part of the barrel 10 and having the usual float 14 for maintaining the gasoline or other liquid fuel at the level indicated at 15. Within the float bowl are two or more vents 16 above the liquid level and one or more openings 17 slightly below the liquid level as shown, the top of the float bowl being sealed by the cover 13a. In the operation of the engine the liquid fuel in the float bowl passes out of the opening 17 and is consumed by the engine, causing the float 14 to drop to admit sufficient fuel from a fuel supply pipe, not shown, to restore the fuel in the bowl to the level indicated at 15.

The lower part of the barrel 10 includes a circular section 18 and a transition and Venturi section 19. A conventional butterfly throttle valve 20 operable by an external crank 21 is pivotally mounted in the section 18. A suitable adjustable stop is provided for the throttle valve so that in the closed position there is sufficient leakage to operate the engine at idling speed. Fuel for operating the engine at idling speed may be obtained from a conventional throttle edge idling port 22, although, as will be hereinafter pointed out, this port may be entirely eliminated if desired. The port 22 is fed from the opening 17 in the carburetor bowl, or from an independent opening similarly located, which connects with the port 22 through passages formed in the walls of the barrel 10 and the carburetor bowl under the control of an idling adjustment screw 22a in the usual manner. When the port 22 is used it operates in a manner understood in the art to supply fuel only when the throttle valve 20 is nearly closed so as to cause a high velocity emulsion of air and fuel to issue around the edge of the valve blade and past the opening of the

port. This fuel emulsion is produced by an idling jet, not shown, which is of any conventional type as it forms no part of the present invention. At higher engine speeds when the throttle valve is opened to a more nearly vertical position the suction immediately across the opening of the idling port is reduced so that it then becomes inactive and ceases to supply fuel.

In the upper end of the barrel 10 is a transition ring 23 having a circular outside shape to fit in the circular part 11, and having a rectangular or square opening 24 therein. A pair of flexible reeds 25, made of thin, curved spring material such as stainless steel are mounted and secured as by the screws 26 on opposite sides of the opening 24 in inclined positions so as to restrict the opening through the induction passage. The transition ring 23 has a vertical extension 27 within the barrel 10 of square cross section approximating the size of the opening 24, and adapted to fit closely on opposite sides of the reeds 25 with a fairly small clearance. When there is no air flow through the carburetor and the reeds are in relaxed condition they assume the positions indicated in full lines in Figure 3, but their flexibility is such as to allow them to bend backwardly to the broken line position indicated at 25' when a large volume of air is flowing therebetween, and to thereafter flatten out to increase the size of the opening even more at exceptionally high rates of air flow. The reeds thereby form movable side walls of a variable rectangular venturi which is responsive to the volume or rate of air flow.

The ring 23 and vertical extension 27 constitute a cage or holder for the reeds within the induction passage of the barrel 10 whereby they may be easily removed without removing the carburetor barrel from the engine. While the part 27 of the reed cage is shown to be rectangular within, its outside may be either rectangular or circular to fit the shape of the mid section of the barrel 10, but it is preferable to make this part of the barrel also square or rectangular. The reeds and cage 27 may also be of wedge or hour glass shape as viewed in Figure 2 whereby the cage forms two fixed Venturi walls and the reeds form two variable Venturi walls to produce a variable rectangular Venturi throat section. The ring 23 provides a transition section between the circular barrel end 11 and the rectangular venturi, and the fixed venturi 19 provides a transition section back to the circular lower end 18. Other purposes and advantages of the venturi 19 will be mentioned hereinafter. The lower ends of the reeds are curved to allow a smooth air flow away from the throat of the venturi.

The lower end of each reed is provided with an elongated opening 28 to surround a similarly shaped fuel allocator 30 extending transversely across the induction passage at right angles to the reeds. The fuel allocator is relatively thin and shaped to offer a minimum obstruction to the flow of air through the carburetor. Its top and bottom edges are curved as indicated at 31 and 32, to conform to the sweep of the reed openings while at the same time maintaining a fairly small clearance therewithin. The curved edges 31 and 32 are substantially parallel whereby the fuel allocator has a uniform height throughout its length so that it can be inserted and removed through openings 33 in one side of the barrel and reed holder. A tapped hole 34 in one end of the body of the fuel allocator provides attachment for 75 a handle piece for removal of the fuel allocator.

When the fuel allocator 30 is inserted through the hole 33 the leading end is received in a similar hole 35 in an opposite wall of the extension 27 and seated against the inner wall of the barrel 10, in which position it may be held by a screw 36 and by other parts which will now be described. When the fuel allocator is thus assembled in the barrel, a horizontal gallery passage 37 registers with a fuel passage 38 which is connected with the opening 17 in the carburetor bowl, a gasket 39 being provided to seal the joint between the parts. A drain plug 38a is provided to drain the passage 38 if desired when the allocator is removed. A plurality of vertical fuel passages 40 rise from the gallery passage 37 at intervals along the length of the fuel allocator and communicate with jets hereinafter described and pairs of discharge ports 41 exposed on opposite side surfaces of the allocator and symmetrically disposed on opposite sides of the central or rest position of the reeds. The vertical position of the fuel allocator 30 with respect to the carburetor bowl is such that the quiescent liquid level stands in an intermediate position in the riser passages 40 above the level of the gallery passage 37 and below the level of the discharge ports 41 when the air pressures in the induction passage and carburetor bowl are equalized. Vents 42 behind the reeds communicate with the openings 16 in the carburetor bowl to maintain this equilibrium of pressure at all times for those of the ports 41 which are disposed behind the reeds, and for all of the ports when there is no substantial air flow passing through the carburetor to produce a depression between the reeds. Thus, fuel will issue only from those ports which are exposed to pressures depressed below the pressure existing on top of the liquid in the carburetor bowl as determined by the positions of the reeds relative to the ports.

Extending through the vertical fuel passages 40 is a fuel flow impairment valve 45 which may be adjusted by an external lever 46. This valve comprises a rotatable shaft or rod extending through a sleeve 48 which may be screwed into the body of the fuel allocator when the latter is installed in the barrel 10. A pair of nuts 47 hold the parts in place to provide a rigid bearing for rotation of the valve shaft and lever and permit the sleeve to be unscrewed when the fuel allocator is to be removed, whereby the sleeve assists the screw 36 in securing the allocator rigidly in the barrel. This valve is preferably located above the quiescent fuel level in the passages 40 so as to obviate the necessity for packing to prevent leakage when the carburetor is not in operation. When the carburetor is operating, the impairment valve is either at or below atmospheric pressure so there can be no leakage.

The fuel flow impairment valve 45 provides a means for adjusting the relative discharge rates of fuel through the various discharge ports 41 in order to best satisfy the varying demands of an internal combustion engine under different operating conditions. This is accomplished by forming valve sections on the valve shaft 45 having different orifice characteristics and indexed to different relative angular positions to effect different valve openings in the various passages 40 which supply the ports 41. Non-adjustable means will also be described for this purpose employing jet orifices in the passages 40 having different discharge coefficients to modify the discharge into ports 41 in response to changes in the effective fuel head under different operating

conditions. While the adjustment provided by the valve 45 does not need to be changed in the ordinary operation of the carburetor it is useful to raise or lower the mixture curve and is of value in engine operation at changing altitudes or with various grades of fuel.

Referring now to Figures 4 to 8, the fuel allocator and two forms of fuel flow impairment valve are shown on an enlarged scale. For convenience in manufacture, and for other reasons the fuel allocator is preferably made in two parts, the body 30 being a permanent member and having an upper part or cap 50 secure thereto by means of screws 51 and containing horizontal bores which form the discharge ports 41, and vertical bores communicating with the upper ends of the vertical fuel passages 40. As shown in Figures 4 and 5, the valve 45 may comprise simply a cylindrical rod passing through the vertical fuel passages 40 and having a diameter equal to the diameter of these passages. The rod is of cylindrical cross section between these passages and is ground off or relieved as shown at 55 in certain passages to partially open the passage and exert a restrictive action on the fuel flow therethrough in accordance with the angular position of the rod. The contour of each relieved portion 55 is such as to allow a smooth passage of the fuel, the discharge characteristic being that of a rounded orifice. The conditions necessary to obtain this characteristic are a smooth, rounded curvature of the part 55 to minimize cross flow, and a riser section in the passage 40 comparable with the valve dimensions. There should be no abrupt changes in the riser section and it should be of ample capacity to minimize any square edge orifice effects at the junction of the riser passages 40 and the supply gallery 37. The relieved portions 55 may be formed entirely on one side of the shaft, as shown, or on opposite sides to produce a more symmetrical flow in the upper end of the riser passage.

Figures 6, 7 and 8 illustrate a form of fuel flow impairment valve having square edge orifice characteristics. In this case the rod 45 is ground off to present a flat side 55a in each of the riser passages 40, and each of these passages is provided with an insert 56 closely fitting the rod 45. Each insert 56 is provided with an opening 57 in the form of a slit disposed at right angles to the axis of the valve rod whereby the slit is gradually uncovered by the flat side 55a as the rod is rotated. Since the surface 55a extends at right angles to the direction of the slit, the area of the slit opening varies as a linear function of the angular movement of the valve rod, thereby enabling a precise indexing of the valve action in the several fuel passages and an accurate calibration of the valve in order to obtain a desired setting thereof. The condition necessary to obtain a square edge discharge characteristic is that the section of the riser passage 40 should be large in comparison to the discharge slit area, the ratio preferably being at least four to one to obtain appreciable side flow.

As will be hereinafter pointed out, it is intended to employ round orifice valves as shown in Figure 5 in certain of the riser passages, and square edge orifice valves as shown in Figure 7 in other of the riser passages, but it is within the scope of the invention to make all the valves on shaft 45 of the same type but indexed to different angular positions.

Figures 9 to 12 illustrate different forms of non-adjustable fuel allocator having various

types of fixed orifices in lieu of the adjustable fuel flow impairment valve 45. In Figure 9 the cap 50 has transverse passages 60 drilled therein to form the pairs of discharge ports 41, as in the preceding illustrations. Vertical bores 61 connect each passage 60 with one of the vertical fuel passages 40 and the body 30. In this case the bores 61 comprise the jets and are smaller than the riser passages 40 to form square edge orifices at 62 on the bottom surface of the cap member.

In Figure 10 the vertical bore 61 is enlarged at its lower end in a gradual taper 63 forming a round edge type orifice between the riser 40 and the upper part of the bore 61.

In Figures 11 and 12 removable and interchangeable inserts are employed to form either round or square edge orifices, as desired, in the different fuel passages. Thus the vertical passage 40 is enlarged for some distance at 64 to receive either the insert 65 shown in Figure 11 or the insert 67 shown in Figure 12, and the cap member is of less height. The insert 65 has a square edge orifice 66 interposed between the vertical passage 40 and the bore 61, and the insert 67 has a round edge or tapered orifice 68 which maintains streamlined flow as the cross sectional area is reduced from that of the vertical passage 40 to that of the upper body of the insert. The length of enlarged portions 64 allows jet inserts of different length to diameter ratios, as well as different tapers to be used.

Figure 13 illustrates a fuel allocator having seven non-adjustable jets of different characteristics. The body 70 is formed with a gallery passage 37 and a plurality of vertical riser passages 40 to be supplied from a fuel passage 38 as in Figure 3. The cap 71 is formed with vertical fuel passages communicating with the risers 40, and horizontal passages forming discharge ports at their opposite ends as in the previous embodiment. In this case the central vertical passage in the cap 71 is tapered to form a round edge or tapered orifice 72, and the two adjacent vertical passages on either side are shouldered to form square edge orifices 73. The two end passages 74 have the same size bore in the cap 71 as in the body 70 to promote a large unimpaired flow of fuel when these jets are brought into action. At low engine speeds the reeds 25 include in the rectangular Venturi opening only the central jet having the round orifice 72. At higher speeds and loads the square edge orifice jets are included, and finally, under conditions of maximum air flow, the reeds 25 spread apart sufficiently to include and render active the end jets 74. The reason for these different types of jets in this particular arrangement will be discussed hereinafter in connection with the operation of the device.

In Figure 14 is illustrated a modification having three non-adjustable jets. In this construction the fuel allocator 80 has a gallery passage 37 communicating with three riser passages 40 leading to three pairs of ports 41. The two outer vertical passages in the cap 81 may be shouldered to form square edge orifices 73 of the type employed on the four intermediate jets in Figure 13, and the central vertical passage may be internally tapered to form a rounded orifice 72. In Figure 14 all three of the jets 72 and 73 are made active when the reeds 25 are spread to the position shown in full lines under conditions of high speed and load. In light running, or cruising, and in idling, only the central jet 72 is in operation, the reeds closing up to the position shown at 25" in idling.

Thus the two outside jets 73 may be termed power jets, an important feature of the invention being that these power jets are activated automatically by reed deflection according to the engine demands, instead of by a mechanical action connected with the throttle as has been a conventional mode of control of power jets in the prior art.

Figure 15 illustrates a modified construction in which the reeds are inverted. The vertical downdraft carburetor barrel 84 here contains a non-adjustable fuel allocator 85 having a cap 86 with a plurality of ports 41. This allocator may be of the type shown in Figures 13 or 14, or it may be of the variable type illustrated in Figures 4 to 8. Surrounding the fuel allocator and fitting closely within the barrel 84 is a reed cage or holder 87 having a lower end portion 88 designed to form a transition section in which are mounted the upwardly directed scoop-line reeds 90. The reeds are illustrated in an intermediate position corresponding to a medium power output, from which position they are movable in both directions to increase or decrease the number of discharge ports 41 included in the variable Venturi opening. At idling speeds the reeds assume a position close together on opposite sides of the central ports, and at high speeds the reeds are pushed apart by the in-rushing air to include all of the ports 41 therebetween. In order to accommodate the extreme movements of the upper ends of the reeds the barrel 84 is flared on opposite sides at 91 to receive the tips of the reeds so that the end ports may be uncovered. The barrel may be made in two pieces to facilitate the shaping thereof.

The upper end of the barrel 84 is circular and a transition section may be provided if desired between this circular end and the variable rectangular opening between the reeds. At the lower end of the reeds the end portion 88 of the cage forms a transition section from the rectangular Venturi opening back to the circular shape of the lower end of the barrel. Above the end portion 88 the cage 87 has a square or rectangular inner opening with parallel side walls lying closely adjacent the edges of the reeds so that all the air passing through the carburetor barrel is thereby forced between the reeds. The cage and reeds may be of hour glass shape, viewed at right angles to Figure 15, as previously mentioned in connection with Figure 2, to centralize the air flow around the central ports at idling and low running speeds. The central ports may then serve as idling ports in lieu of the usual throttle edge idling port. The upper ends of the reeds are curved outwardly so that they will be forced apart in the manner described by the inrushing air. In this arrangement the carburetor float bowl 13 is vented to atmosphere as the spaces behind the reeds are at substantially atmospheric pressure.

The arrangement shown in Figure 16 may be utilized to increase the velocity of air flow over the central ports 41 in the fuel allocator 30 at idling speeds so that the throttle edge idling port 22 may be eliminated. Here the reeds 95 are formed and mounted to spring together at 98 to completely close the Venturi throat except for a small opening 96 to include the central ports. The size of this opening is determined by deformed portions 97 in the reeds which extend only slightly on either side of the fuel allocator to centralize the air flow when the reeds

are closed together as shown. A sufficient depression is thereby produced in the opening 96 to activate the central ports at idling speeds. If desired, the central ports may be placed in a lower position closer to the quiescent fuel level in the riser passages in the construction of Figure 16 and also in the other embodiments to provide adequate discharge at the idling depression. At higher speeds and loads the reeds are deflected apart by the inrushing air as in the case of reeds 25 to increase the Venturi opening and the number of Venturi ports in accordance with the engine demands. The deformed portions 97 need extend only for a short distance along the reeds where their curvature brings them close together above and below the line of contact at 98. This form of reed may be used in any of the different embodiments hereinabove described. If employed in Figure 15 it would have the advantageous effect of reducing the spread of the reeds to uncover all the discharge ports, so that the flares 91 in the barrel would be unnecessary.

Operation

In the different embodiments it will be apparent that the two flexible reeds are deflected by the inrushing air so as to be separated to form a variable rectangular venturi in accordance with the demands of the engine, the reeds automatically changing the size of the opening therebetween according to the volume of air which is required by the suction displacement of the engine. The movement of the reeds uncovers and brings into action additional fuel jets as required to maintain the desired air fuel mixture ratio for larger volumes of air without depending entirely upon increased flow from the jets which are first in operation. The discharge capacities and/or coefficients of the active jets thereby modify the mixture ratio for different engine demands whereby the mixture ratio may be caused to vary according to a predetermined curve to meet the particular needs of different operating conditions of an internal combustion engine.

The reeds and the two sides of the holder comprise a rectangular air conduit of variable net cross sectional area in the Venturi throat, which area is a function of the reed's deflection from a central, normal or rest position. The design of the parts is such that the maximum net area occurring when the reeds are fully deflected provides sufficient capacity to accommodate the engine's greatest air demands. In all embodiments the pairs of discharge ports 41 are symmetrically disposed with respect to the central or rest position of the reeds, and the ports are designed to give a symmetrical and quadrant fuel discharge. That is to say that the discharge is symmetrical and equal in all four quadrants of the cross sectional area of the Venturi throat for all positions of the reeds. The jets may be of any type. Some or all of them may be of the submerged type and the jets and discharge ports may be mounted from the carburetor bowl or reed cage, if desired, rather than in a transversely extending fuel allocator, although the latter arrangement is utilized in the present embodiments to illustrate the operating principles of the invention.

When an internal combustion engine is in operation with the present carburetor in any of its various forms, the reeds are deflected in the manner described by the inrushing air, their de-

flection being a measure of the quantity of air flowing through the carburetor. As the reeds deflect, a greater number of discharge ports or jets are included in the Venturi flow to supply an increasing quantity of fuel to the greater quantity of air. The flow of air through the induction passage and between the reeds is produced by a pressure gradient established by the suction of the engine whereby the pressure in the intake manifold is depressed below atmospheric pressure. The action of the air flow between the reeds produces local variations in pressure in different parts of the carburetor which are utilized to bring additional jets into action in accordance with the principles of the invention. The jets behind the reeds are maintained inactive by equalizing the pressure behind the reeds and the pressure on the surface of the fuel in the carburetor bowl through the communicating ports 16 and 42. Fuel in the riser passages 40 behind the reeds is therefore exposed to the same pressure through the ports 41 as the fuel in the carburetor float bowl whereby the fuel in these passages is maintained at the float bowl level and does not issue through ports 41. The ports in the Venturi opening between the reeds however are exposed to a lower pressure by reason of the air velocity, causing fuel to discharge therefrom. The parts are designed so that the differential depression thus created is always in excess of the minimum head necessary to discharge the fuel. This minimum head consists of that head necessary to overcome the surface tension of the fuel plus the vertical height from the quiescent fuel level to the port openings 41. The fuel which is discharged into the high velocity air stream between the reeds is atomized and carried on to the engine induction system. In passing the transition and Venturi section 19 the atomized fuel becomes more thoroughly distributed and mixed in the flowing air stream. The differential or velocity depression causing fuel flow from the active ports is controlled by the dimensions of the air intake conduit system comprising the reeds and holder sides, and the stiffness of the reeds.

There is an advantage in large jet and port areas in that the possibility of the passages and openings becoming obstructed with foreign matter is greatly reduced. By a suitable selection of air flow areas and reed stiffness the differential depression may be made just sufficient to flow the fuel through the jets at the desired discharge coefficient, while at the same time a major portion of the velocity potential in the air intake stream can be exploited. The effectiveness of fuel atomization in fine particles appears to be a function of the square of the relative velocity of the air with respect to the fuel.

It is apparent that by suitable arrangement of jets of various sizes and characteristics in the fuel allocator any air fuel mixture for any engine range can be obtained. For automotive use a mixture ratio of about 12 to 1 is desirable for low speed operation at near idling speeds. At part throttle conditions in the normal or cruising range, economy is desirable and mixtures of 15 to 1 are preferred. From about three-quarter to full throttle a mixture ratio of about 12 to 1 is necessary for providing maximum power. An air fuel mixture curve of this type may be effected by appropriate selection of jet discharge area, jet type, and port placement in the fuel allocator with respect to reed deflection increment.

The shape of the air fuel mixture curve may

be controlled in the adjustable fuel allocator by the relative indexing of the different valve portions on the valve rod 45 in the several vertical fuel passages, and by the use of round edge orifice valves in certain risers and square edge orifice valves in other risers, as illustrated in Figures 5 and 7. In the non-adjustable fuel allocator the shape of the mixture curve may be controlled by the use of different sizes and types of orifices in the different jets as illustrated, for example, in Figures 9 to 13. Round edge orifices have a relatively linear discharge curve and flat or plate type orifices have a flattened discharge curve, with reference to discharged quantities plotted against head in inches of water. For low engine loads and idling it may be desirable, though not necessary, to have a separate low-load and idling carburetor port such as the port 22 in Figure 3 which is preferably operative up to approximately 450 R. P. M. in the case of automotive engines. At this speed it is preferred that the central jet of the main jet assembly in the fuel allocator gradually commence to discharge. It is also desirable that this transition point be passed with smoothness and without abrupt change in mixture ratio. Since the central jet supplies the fuel for light to moderate loads, its characteristic should be somewhat linear. This may be accomplished in the non-adjustable allocator by using a rounded orifice such as shown at 72 in Figure 13 or either of the types shown in Figures 10 and 12. In the adjustable allocator, Figure 5 may be considered as illustrating the central jet.

When the load, and consequently air volume, increases to the point where the discharge of the central jet becomes insufficient the diverging reeds bring additional jets into action. It is desirable then that the initiation of discharge from the additional jets be slightly more abrupt than the central jet, and also that they have flatter characteristic curves at higher loads. These additional jets should become effective when the central jet is at or near maximum discharge, and provide a lean mixture through their range, their discharge supplementing that of the central jet. A number of these jets activated in steps is desirable to include a wide range of speeds.

At high engine loadings the final or power jets at the ends of the fuel allocator become active. Their discharge characteristics should also be somewhat linear and add to the aggregate jet discharge sufficient fuel to provide a mixture of maximum power.

In a symmetrical arrangement of seven jets the preferred embodiment is to employ round orifice characteristics in the central and end jets, and square edge orifice characteristics in the four jets intermediate therebetween. Thus, referring to Figure 13 as an example, the central pair of ports are served by the round edge orifice 72 and the end pairs of ports are fed by the vertical passages 74 which also have round edge orifice characteristics. The other four pairs of ports intermediate between the central and end pairs are fed through the four square edge orifices 73. The same mixture curve may, of course, be obtained by use of the jet and orifice types shown in Figures 5, 7, and 9 to 12 as hereinabove explained.

Other jet and orifice arrangements may be used, but a primary advantage of the invention is that it is possible by the proper selection of jet characteristics in the individual riser pas-

sages to produce a mixture of maximum economy or power at any predetermined value or values of engine loading.

The fineness of mixture control is dependent on the number of jets available for progressive activation in the fuel allocator system. With seven or more jets, extremely close regulation of the mixture curve is possible. A fewer number of jets may be used, however, as illustrated in Figure 14 where there are three jets. In this arrangement, the central jet supplies, or meters, sufficient fuel for light loads and economical cruising ranges corresponding to partial throttle openings. With wide open throttle conditions the remaining two jets are activated, their discharge supplementing that of the central jet and providing a mixture of maximum power, whereby the two outside jets may be termed power jets. The reeds are shown in full lines in positions to produce full discharge from all the jets, and in broken lines in a low speed position.

As has been previously stated, it is not necessary that the different jets all be at the same level with respect to the quiescent fuel level in the vertical risers 40. If the idling jet 22 is dispensed with, its function may be accomplished by a central jet or jets in the fuel allocator, particularly if these jets are located relatively close to the quiescent fuel level, as mentioned in connection with Figure 16. It may then be desirable to place the port openings 41 at different heights, and possibly to employ the port openings themselves as jets.

The present variable venturi has a beneficial corrective effect upon an undesirable condition in many conventional carburetors known as "throttle bias." At partial openings of the usual butterfly throttle valve, particularly in the region of 45° of angular rotation with respect to the carburetor barrel, the quantity and velocity of the flowing medium passing the throttle plate edge on one side is considerably greater than that passing on the other side. The angular position of the throttle plate tends to concentrate the medium on one side and to rarify it on the other side by producing in effect a Venturi orifice in one side of the pipe or barrel, and a re-entrant orifice in the other side which deflects and stratifies the fuel in the incoming mixture against one side of the manifold producing non-homogeneity of the mixture finally reaching the engine cylinders. At certain speeds there is a tendency in conventional carburetors as a result of this condition for some cylinders to receive too lean a mixture while others receive too rich a mixture, a condition which has been difficult to remedy without complicating the construction of the throttle valve.

The restricted Venturi passage between the reeds acting in conjunction with the transition and Venturi section 19 tends to centralize and focus the flow of mixture in the center of the carburetor barrel as it approaches the throttle valve, thereby making for a more equitable distribution of the mixture on both sides of the throttle plate. Or, looking at the fuel flow from a different view point, the air between the reeds is subject to suction from somewhat of a point source in the Venturi section 19 which promotes mixing and tends to reduce stratification of the mixture immediately approaching the throttle valve. Thus, further advantage of the present arrangement is the deflection and intermingling of the fuel mixture ahead of the throttle valve and the free symmetrical flow of the mixture

due to the absence of projecting jets or other obstructions in the venturi 19. Since there are no obstructions in the venturi 19, it can be made with a smaller net section than conventional venturis, thereby resulting in increased deflecting and focusing and centralizing actions. The venturi 19 acts both as a point source of suction for the variable venturi and as a point source of supply for the mixture flowing toward the throttle valve, tending to reduce separation of the fuel.

Although the throttle valve is shown mounted for rotation on an axis parallel with the reeds it may be turned at right angles or in any other relative position because of the centering and focusing of the flow by the venturi 19 in the manner just described.

In order to simplify and clarify the explanation of the principles of the invention no throttle pump or choke have been shown, but it is intended that the present carburetor should be supplied with such equipment. A conventional throttle pump may be employed and the usual choking methods may be used for starting. The choke may comprise the usual butterfly valve ahead of, or in the leading end of, the carburetor barrel, referred to the direction of air flow in the induction system. The action of the choke should be such as to cause the entire jet system to discharge fuel upon full choke. If the choke is automatic it should be arranged so that the choking action will be materially reduced as soon as sufficient fuel is in the intake manifold for starting.

The various modifications herein illustrated are intended to operate as down-draft carburetors, but the carburetor barrel may, if desired, be turned horizontally or even inverted to serve as an up-draft carburetor without sacrificing any of the advantages of the invention except the recognized advantages of having a down-draft flow of the fuel mixture into the engine.

As has been mentioned hereinabove it is not essential to the invention that the discharge ports be mounted and arranged in a transverse fuel allocator of the specific construction shown. The ports may be mounted in various ways in the carburetor barrel so as to be activated successively by movements of the reeds.

The reeds have been described as made of flexible material capable of bending to admit the necessary volume of incoming air, but it is apparent that they may be otherwise constructed and still perform the same function. They may, for instance, take the form of rigid hinged vanes which are biased to close together to a certain minimum Venturi opening, and adapted to spread apart to uncover additional fuel ports with an increasing volume of air.

Still other changes may be made in the construction and arrangement of parts and in the use of certain features without others, and all such modifications within the scope of the appended claims are deemed to be included in the invention.

Having now described my invention and in what manner the same may be used, what I claim as new and desire to protect by Letters Patent is:

1. A carburetor comprising an induction passage, a throttle valve in said passage, a multiple jet fuel allocator in said passage ahead of said throttle valve, a variable venturi associated with said fuel allocator to expose a number of fuel jets to the air flow through the venturi in proportion to the volume of air flowing through said passage, all of said jets being open and capable

5 of discharging fuel when exposed to the air flow in said venturi, and a fixed Venturi section in said passage between said throttle valve and said fuel allocator to assist in mixing the air and fuel and to centralize the mixture flow in said passage leaving said fuel allocator and approaching said throttle valve.

2. In a carburetor, an induction passage having an air intake opening at one end and a throttle valve at the other end, a pair of flexible reeds on opposite sides of said passage between said intake opening and said throttle valve, said reeds having free elastic response to air flow through said passage to form a variable venturi, a horizontal fuel allocator extending across said passage between said opposite sides perpendicular to said reeds and in the region swept by the movements of said reeds, and a series of open fuel discharge ports spaced along said allocator, the central one of said ports being included in the throat of the venturi at all times and the remaining ports being included in variable number as the reeds move apart in response to increasing air flow.

3. In a carburetor, an induction passage having an air intake opening, a throttle valve spaced from said intake opening, a pair of flexible reeds on opposite sides of said passage between said intake opening and said throttle valve, said reeds having free elastic response to air flow through said passage to form a variable venturi, a horizontal fuel allocator extending across said passage between said opposite sides perpendicular to said reeds and in the region swept by the movements of said reeds, a series of fuel discharge ports spaced at intervals along said allocator, all of said ports being open at all times, and means for maintaining liquid fuel in said allocator at such level that only those ports exposed to the reduced pressure in the throat of the variable venturi will discharge fuel while those ports behind said reeds on opposite sides of said passage will not discharge fuel.

4. In a carburetor, vertical induction passage, a pair of flexible reeds on opposite sides of said passage having free elastic response to air flow through said passage to form a variable venturi in the center of said passage, a horizontal fuel allocator extending across said passage between said opposite sides perpendicular to said reeds in the region swept by the movements of said reeds, a series of open fuel discharge ports spaced along said allocator to be exposed in variable numbers to air flow through said venturi between said reeds depending upon the positions of said reeds, the remaining ports being shielded from said air flow in spaces behind said reeds at said opposite sides of the passage, a float bowl connected with said allocator to maintain a predetermined quiescent liquid fuel level in said allocator below the level of said ports, and vent passages connecting said spaces behind the reeds with the top of said float bowl to equalize the air pressure in said float bowl with the pressure existing in said spaces for preventing fuel discharge from the ports in the spaces behind the reeds.

5. In a carburetor, a vertical induction passage having an air intake at its upper end and a throttle valve at its lower end, a fixed venturi above said throttle valve, said passage having an approximately square cross section for a distance above said fixed venturi, an elongated horizontal fuel allocator extending across said passage in said square cross section, fuel ports spaced along said allocator, and a pair of vertical rectangular free

reeds extending across said square section transversely to the length of said fuel allocator with openings closely fitting said allocator and biased toward each other to form a variable venturi exposing the central one of said ports to a small volume air stream and exposing additional ports on opposite sides of said central port when the reeds are spread apart by a large volume of air flow.

6. In a carburetor, a vertical induction passage having an air intake at its upper end and a throttle valve at its lower end, a fixed venturi above said throttle valve, said passage having an approximately square cross section for a distance above said fixed venturi, an elongated horizontal fuel allocator extending across said passage in said square cross section, fuel ports spaced along said allocator, a longitudinal fuel passage in said allocator, individual riser ducts connecting said ports with said fuel passage, round edge type orifice means in certain of said ducts and square edge type orifice means in other of said ducts, and a pair of vertical rectangular free reeds extending across said square section transversely to the length of said fuel allocator and having openings closely fitting said allocator to form a variable venturi exposing the central one of said ports to a small air stream through said variable venturi and exposing additional ports on opposite sides of said central port when the reeds are spread apart by a large volume of air flow.

7. In a carburetor, a vertical induction passage having an air intake at its upper end and a throttle valve at its lower end, a fixed venturi above said throttle valve, said passage having an approximately square cross section for a distance above said fixed venturi, an elongated horizontal fuel allocator extending across said passage in said square cross section, fuel ports spaced along said allocator, a fuel passage extending longitudinally through said allocator, individual riser ducts connecting said ports with said fuel passage, a common rotatable valve rod intersecting all of said ducts, said rod being relieved in rounded contour in certain of said ducts to form round edge orifices and relieved in angular contour in other of said ducts to form square edge orifices, and a pair of vertical rectangular free reeds extending across said square section transversely to the length of said fuel allocator and having openings closely fitting said allocator to form a variable venturi exposing the central one of said ports to a small air stream through said variable venturi and exposing additional ports on opposite sides of said central port when the reeds are spread apart by a large volume of air flow.

8. In a carburetor, a straight induction passage having a portion with an approximately square cross section, an air intake opening at one end of said passage and a throttle valve at the other end, an elongated horizontal fuel allocator extending across said passage in said square cross section, fuel ports spaced along said allocator, a pair of free reeds on opposite sides of said passage disposed transversely of said fuel allocator and biased toward each other, said reeds having side edges closely fitting the walls of said passage with small clearance and having openings closely fitting said allocator with small clearance to form a variable venturi exposing the central one of said ports to a small air stream and

exposing additional ports on opposite sides of said central port when the reeds are spread apart by a large volume of air flow.

9. In a carburetor, an induction passage having an air intake opening at one end and a throttle valve at the other end, a pair of flexible reeds on opposite sides of said passage between said intake opening and said throttle valve, said reeds having free elastic response to air flow through said passage to form a variable venturi, a horizontal fuel allocator extending across said passage between said opposite sides perpendicular to said reeds and in the region swept by the movements of said reeds, a series of open fuel discharge ports spaced along said allocator, the central one of said ports being included in the throat of the venturi at all times and the remaining ports being included in variable number as the reeds move apart in response to increasing air flow, a longitudinal fuel passage in said allocator, individual riser ducts connecting said ports with said fuel passage, round edge type orifice means in certain of said ducts, and square edge type orifice means in other of said ducts.
10. In a carburetor, an induction passage having an air intake opening at one end and a throttle valve at the other end, a pair of flexible reeds on opposite sides of said passage between said intake opening and said throttle valve, said reeds having free elastic response to air flow through said passage to form a variable venturi, a horizontal fuel allocator extending across said passage between said opposite sides perpendicular to said reeds and in the region swept by the movements of said reeds, a series of open fuel discharge ports spaced along said allocator, the central one of said ports being included in the throat of the venturi at all times and the remaining ports being included in variable number as the reeds move apart in response to increasing air flow, a fuel passage extending longitudinally through said allocator, individual riser ducts connecting said ports with said fuel passage, and a common rotatable valve rod intersecting all of said ducts, said rod being relieved in rounded contour in certain of said ducts to form round edge orifices and relieved in angular contour in other of said ducts to form square edge orifices.
- 25 11. In a carburetor, an induction passage having an air intake opening at one end and a throttle valve at the other end, a pair of flexible reeds on opposite sides of said passage between said intake opening and said throttle valve, said reeds having free elastic response to air flow through said passage to form a variable venturi, a horizontal fuel allocator extending across said passage between said opposite sides perpendicular to said reeds and in the region swept by the movements of said reeds, a series of open fuel discharge ports spaced along said allocator, the central one of said ports being included in the throat of the venturi at all times and the remaining ports being included in variable number as the reeds move apart in response to increasing air flow, a fuel passage extending longitudinally through said allocator, individual riser ducts connecting said ports with said fuel passage, and a common rotatable valve rod intersecting all of said ducts, said rod being relieved in rounded contour in certain of said ducts to form round edge orifices and relieved in angular contour in other of said ducts to form square edge orifices.
- 30 12. In a carburetor, an induction passage having an air intake opening at one end and a throttle valve at the other end, a pair of flexible reeds on opposite sides of said passage between said intake opening and said throttle valve, said reeds having free elastic response to air flow through said passage to form a variable venturi, a horizontal fuel allocator extending across said passage between said opposite sides perpendicular to said reeds and in the region swept by the movements of said reeds, a series of open fuel discharge ports spaced along said allocator, the central one of said ports being included in the throat of the venturi at all times and the remaining ports being included in variable number as the reeds move apart in response to increasing air flow, a fuel passage extending longitudinally through said allocator, individual riser ducts connecting said ports with said fuel passage, and a common rotatable valve rod intersecting all of said ducts, said rod being relieved in rounded contour in certain of said ducts to form round edge orifices and relieved in angular contour in other of said ducts to form square edge orifices.
- 35 13. In a carburetor, an induction passage having an air intake opening at one end and a throttle valve at the other end, a pair of flexible reeds on opposite sides of said passage between said intake opening and said throttle valve, said reeds having free elastic response to air flow through said passage to form a variable venturi, a horizontal fuel allocator extending across said passage between said opposite sides perpendicular to said reeds and in the region swept by the movements of said reeds, a series of open fuel discharge ports spaced along said allocator, the central one of said ports being included in the throat of the venturi at all times and the remaining ports being included in variable number as the reeds move apart in response to increasing air flow, a fuel passage extending longitudinally through said allocator, individual riser ducts connecting said ports with said fuel passage, and a common rotatable valve rod intersecting all of said ducts, said rod being relieved in rounded contour in certain of said ducts to form round edge orifices and relieved in angular contour in other of said ducts to form square edge orifices.
- 40 14. In a carburetor, an induction passage having an air intake opening at one end and a throttle valve at the other end, a pair of flexible reeds on opposite sides of said passage between said intake opening and said throttle valve, said reeds having free elastic response to air flow through said passage to form a variable venturi, a horizontal fuel allocator extending across said passage between said opposite sides perpendicular to said reeds and in the region swept by the movements of said reeds, a series of open fuel discharge ports spaced along said allocator, the central one of said ports being included in the throat of the venturi at all times and the remaining ports being included in variable number as the reeds move apart in response to increasing air flow, a fuel passage extending longitudinally through said allocator, individual riser ducts connecting said ports with said fuel passage, and a common rotatable valve rod intersecting all of said ducts, said rod being relieved in rounded contour in certain of said ducts to form round edge orifices and relieved in angular contour in other of said ducts to form square edge orifices.
- 45 15. In a carburetor, an induction passage having an air intake opening at one end and a throttle valve at the other end, a pair of flexible reeds on opposite sides of said passage between said intake opening and said throttle valve, said reeds having free elastic response to air flow through said passage to form a variable venturi, a horizontal fuel allocator extending across said passage between said opposite sides perpendicular to said reeds and in the region swept by the movements of said reeds, a series of open fuel discharge ports spaced along said allocator, the central one of said ports being included in the throat of the venturi at all times and the remaining ports being included in variable number as the reeds move apart in response to increasing air flow, a fuel passage extending longitudinally through said allocator, individual riser ducts connecting said ports with said fuel passage, and a common rotatable valve rod intersecting all of said ducts, said rod being relieved in rounded contour in certain of said ducts to form round edge orifices and relieved in angular contour in other of said ducts to form square edge orifices.
